UNITED STATES PATENT OFFICE

BENJAMIN FILBERT, OF BUFFALO, NEW YORK

APPARATUS FOR SUBMARINE BOATS

Application filed February 4, 1929. Serial No. 337,259.

This invention relates to apparatus, part of which can be used in general to raise submerged objects, but more particularly to apparatus, part of which is carried on submarine boats for locating said boats when submerged and for assisting in saving life on said boats, and part of which is carried on rescue vessels for raising said submarine.

The objects of my invention are to provide built-in means on the submarine by which it may be raised to the surface; cables attached to said built-in means and carried by said submarine; buoys carried in said submarine which can be released to reach the surface of the water with signal lights and which carry means for supplying air and sustenance and communication means to its occupants, and means to raise said cables; and also outside floats to be used in connection with said cables to raise said submarine.

With the foregoing and other objects in view which will appear as the description proceeds, the invention consists in certain features of novelty in the construction, combination and arrangements of parts by which the said objects are attained, the invention being more particularly pointed out in the claims.

It is understood that various changes may be made in the construction and arrangement of parts without departing from the spirit or sacrificing any of the advantages of the invention as set forth in the appended claims.

Referring to the drawings accompanying and forming a part of this specification, wherein like symbols refer to like or corresponding parts throughout the several views and in which the preferred embodiment of my invention is illustrated.

Figure 1 is a transverse vertical sectional view of a portion of a submarine showing a chamber with parts of my improved apparatus housed therein.

Fig. 2 is a vertical sectional elevation of one of my improved buoys.

Fig. 3 is a plan of the door opening into the chamber shown in Fig. 1.

Fig. 4 is a side elevation of my improved float for raising submarines.

Fig. 5 is a bottom view of the float shown in Fig. 4.

Fig. 6 is an end view of the float shown in Fig. 4.

Fig. 7 is a sectional elevation of a check valve in the end of float.

Fig. 8 is a sectional elevation of a check valve in the top of float.

Fig. 9 is a side elevation of a submarine as resting at the bottom of the water and with floats in place for lifting same.

Fig. 10 is an enlarged transverse sectional view of a submarine showing the floats attached as in Fig. 9.

Fig. 11 is a plan of a diagrammatic view of a salvaging vessel and its connections to a float.

Fig. 12 is a transverse sectional elevation of a submerged submarine with its buoys at the surface of the water and connected to cables in said submarine.

Fig. 13 is a view of the submarine similar to that of Fig. 12 and with vessels at the surface having floats attached to the submarine's cables.

Fig. 14 is a transverse sectional elevation through my improved float and showing means of attaching to cables.

Fig. 15 is a section on line 15—15 of Fig. 14.

In the figures, 1 represents the submarine of the conventional type. In Fig. 1 a chamber 2 is provided inside of the submarine 1 as shown and which is air and water tight. 3 is a buoy resting on a coiled line 4 to which it is attached from eyes 5 on its bottom by a V-shaped rod 6. 7 is the part of line 4 leading from rod 6 to the top of coil 4. 8 is a coiled heavy cable enclosing the coiled line 4 and to which it is attached from its top coil to the bottom coil of line 4 by means of the portion 9. Cable 8 is attached at its lower end to a built-in hawser 31 which extends from one side of submarine 1 to the other as shown in Figs. 10, 12 and 13. 10 is an air hose coiled inside of coil 4, one end 11 of which leads up the side of, and is attached to, buoy 3, and the opposite end 12 of which extends through the wall of chamber 2 so its valve 13 can be operated by the occupants of the submarine. 11 and 12, called the ends of

80

85

90

95

100

air hose 10 are of metal, curved downward at their extreme ends as shown and each arranged to be attached to an air pump. Running along beside air hose 10 and attached thereto is a telephone wire 14. 15 is the telephone instrument within the submarine and 16 the telephone instrument in the buoy 3 to be used by a salvage crew.

Below chamber 2 and connected thereto is a valve 17 controlled by hand wheel 18 for flooding said chamber 2 with water from outside of submarine 1 and so equalizing the pressure within and without. The door 19 hinged at 20 is then easily opened by the hand wheel of 21 operating a shaft threaded through a bearing 22, a stuffing box 23, a swivel connection 24, a yoke 25, and a pin 26 sliding in a slot 27. Two of the yokes 25 (see Fig. 3), are connected to the door 19 and spaced apart to allow buoy 3 to pass upward between them when door 19 is open. 19' (Fig. 1) is the open position of door 19. 28 is a heavy rubber gasket to make a tight joint between door 19 and the shell of submarine 1.

The buoy 3, shown in detail in Fig. 2, is hollow and adapted to readily move to the surface of the water when released from the chamber 2. 29 is a storage battery in the buoy 3 to furnish current for the light bulb 30 on the top of said buoy 3. The light bulb 30 is protected by a wire netting as shown and the light is controlled by a switch 32 which is connected to and operated by a piston 33 in a cylinder 34 which extends through the bottom of the buoy 3. The piston 33 is connected to the switch 32 by means of a horizontal arm 35 and a vertical link 36. When the buoy 3 is riding on the water the piston 33 is pressed up by the water to operate the switch 32 and light the bulb 30 and the action of wave motion raising and lowering the buoy 3 and hence its piston 33 is to operate the light switch intermittently and so operate the light intermittently. A wire 77 connected so as to be operated by the switch 32 and light a bulb 78 shown on the telephone instrument 15 in the submarine 1 is provided to form a telltale light and show when bulb 30 is lighted and if the battery 29 is still in condition to furnish light. The receiver and transmitter 79 of phone 16 in the buoy 3 is clamped down so it will stay in place except when removed for the purpose of telephoning. As shown the telephone wires 14 are used for the telltale light 78 but when receiver 79 is removed from telephone 16, connection to light bulb 78 is broken. Separate connecting wire from 77 to 78 could of course be used.

The cover 40 of the buoy 3 is fastened by means of pivoted bolts 39 having wing nuts 37. One of said bolts 39 acts as a pivot by passing through a hole in the cover 40, while the remaining bolts 39 can be moved out of slots, as 38, to a position 39'. 41 is a gasket for making a tight joint between buoy 3 and

its cover 40. On top of the cover 40 is placed suitable instructions as for instance the words "U. S. Submarine No. — in distress below." "Remove cover—telephone inside." "Notify Navy Department to rush help."

As a part of this invention and a convenient means of quickly raising a disabled submarine preferably already equipped with the foregoing built-in hawser 31, I provide a float 42 shown in detail in Figs. 4 to 8. Float 42 is a hollow cylinder with heads 43' dished in for strength and suitably fastened. Intermediate of the ends of float 42 are provided two cylindrical castings as braces or posts 43 fastened vertically therein, each one having a longitudinal hole tapered at 44 from top and 45 from bottom to the center thereof and preferably with tapered metal linings as shown. 46, 46 etc., are metal reinforcement patches welded on the outside of float 42 opposite the ends of posts 43.

As a means of internally reinforcing float 42 and strengthening it against the strain of raising a submarine I provide two channels fastened together to form an I beam 47 at top of float and similar channels to form an I beam 48 at bottom of float. The use of these channels is so they can be more easily formed to surround the ends of the vertical braces 43, than regular I beams, as will be noted in Fig. 5. Four I beams 49 are spaced between top and bottom I beams 47 and 48.

Near the center of the top of float 42 is provided an intake check valve 50 having a ball valve 51 and spring 52 for filling said float with water to sink it and threaded for connecting to an air pump to force the water out and filling with air for raising. At the bottom of each end 43' of float 42 is provided a discharge check valve 53 having a ball valve 54 and spring 55 over said ball 54 stiff enough to hold water for sinking float but adapted to allow discharge of the water when air is forced into intake valve 50. Discharge valves 53 are threaded at 56 to provide suitable connection means for a hose from each end of said float 42 to a salvage ship at the surface of the water to determine when all water is discharged from both ends of said float 42 in case one end of float 42 is higher than the other, and also to provide a shut off valve at the salvage ship as a means of holding any desired air pressure in the float 42 (such connecting hoses are not shown).

Referring to Fig. 11 which shows a diagrammatic view of the connection to a float 42 in the water and a portion of the plan of the deck 66 of a salvage ship on which is a water pump 58, with a pump suction in the water 65 and connected by means of a hose 68 and 69 through a connecting T 60 to the intake check valve 50 on the top of float 42 for the purpose of filling with water said float 42 preparatory to sinking it. 57 is an air compressor connected to the T 60 by means

of a hose 67. 59 and 61 indicate a valve with gauge in the hose lines 67 and 68 respectively. The hose 69 is paid out or reeled in to the float 42 as it sinks or rises by means of the winch 62. The cables 8 and 8 from the submarine 1 at the bottom of the water are run through the holes in the float 42 and connected to winches 63 and 63 to take up the slack as the submarine rises.

10 The method of connecting the float 42 to the cable 8 at or near a submerged submarine and which is novel to this invention is shown in detail in Figs. 14 and 15. A double ended wedge 64 tapering from the center and having a circular transverse section is formed by placing three identical pieces 70, 71 and 72 together and holding them by means of a keeper ring 73. Said keeper ring 73 is formed of two parts and bolted together around a central ridge 74 on the wedge 64. A hole is formed lengthwise of the wedge 64 for the reception of the cable 8 and having teeth 75. The hole through the wedge 64 is of such a size as to allow for free movement of said wedge 64 on the cable 8 when the keeper ring 73 is bolted together and holding the parts 70, 71 and 72 of the wedge 64 together. However, the three parts, 70, 71 and 72 of the wedge 64 have a movement sufficient to allow 15 the teeth 75 to engage and clamp the cable 8 when said wedge 64 is in the taper hole 44 of the float 42 as in Fig. 14. A weight 76 is provided for fitting over and clamping the upper tapered end of wedge 64 when its 20 lower tapered end is in the tapered hole 44 of float 42 and so securely locking the wedge 64 onto the cable 8.

As shown in Figs. 9 and 10 provision is made for four chambers 2 on each side of 25 submarine 1, which would call for the use of four floats 42, two on each side of the submarine 1 and each float 42 using two of the cables 8 from two adjacent chambers 2.

30 The operation of my device is as follows:— When submarine 1 is submerged and it is desired to send the buoy 3 to the surface for help the occupants of the vessel first open the valve 17 by means of a handwheel 18 to allow chamber 2 to be filled with water and 35 so equalize the pressure on both sides of the door 19. The door 19 then can be opened by operating the handwheel 21 and moving door 19 to a position 19' when the buoy 3 is free to rise to the surface of the water, carrying the line 4. Line 4 must be of sufficient length to reach the surface from all depths at which a 40 submarine could be rescued as also must be the cable 8 which is attached to the line 4 and to the submarine by means of the built-in hawser 31. The buoy 3 having reached the surface of the water and its electric light bulb 30 having been lighted by the pressure of the water on the piston 33 and so moving the lighting switch 32 a signal is flashed to 45 any vessels which may be in sight. If there

are waves which raise and lower the buoy 3 its light will be flashed intermittently as before described and for the purpose of attracting attention as well as saving the battery. One buoy at a time can be released as 50 the battery in the first buoy sent up becomes discharged and so on. The condition of battery 29 is shown by snapping on the telltale light bulb 78 which is connected with said battery through the medium of wire 77 as 55 before described.

The valve 13 on the air hose 10 can be kept open as only a small amount of water will enter from the time the chamber 2 is filled with water until the buoy 3 reaches the surface of the water, or it can be kept closed and then opened by the occupants of the submarine after said buoy 3 reaches the surface of the water. Either end of air hose 10 can be attached to an air pump for exhausting 60 or supplying air to the submarine and the same air hose 10 can be used to supply liquid food to the occupants of the submarine.

65 Rescuers arriving at the buoy 3 can telephone to the submarine 1 below after removing cover 40, and also the said cover 40 has information on top to obtain vessels with floats 42 for raising said submarine 1. Fig. 12 shows submarine 1 at the bottom with two buoys 3 at the surface of the water. Upon the arrival of rescuing ships with floats 42 the buoys 3 with attached lines 4 are hauled aboard and cables 8 raised and disconnected from said lines 4. Cables 8 are passed through holes in floats 42, wedges 64 and 70 weights 76 and attached to the winches 63.

75 After the floats 42 are overboard from the rescue ships 66 in the positions shown in Figs. 11 and 13 they are flooded with water by means of pump 58 and sunk with the wedges 64 and weights 76 following when they assume the position shown in Figs. 9 and 10. Air is now pumped into the floats 42 by 80 means of the air pump 57 and the water forced out, making the floats 42 buoyant. As floats 42 tend to rise their tapered holes 44 force the parts 70, 71 and 72 of the wedges 64 together so their teeth 75 grip the cables 8 and raise the submarine 1 to the surface, it being understood that floats of sufficient 85 buoyance are furnished to do the work.

90 It will also be understood that the floats 42 and their accessories here described can be used to raise submarines or other submerged objects by fastening cables to suitable 95 means of attachment furnished on said submarines or by cables drawn around the outside of said submarines.

Having thus described my invention what I claim as new is:

100 1. In a salvaging apparatus, a buoyant submersible float having intake and discharge check valves, a vertical brace in said float having a longitudinal tapered hole therethrough, a lifting cable to pass through said tapered 105 110 115 120 125 130

holes; a wedge, double tapered from the center, and formed in sections with a longitudinal toothed hole therethrough with a keeper ring for said sections, a lifting cable to pass through the hole in said wedge and said float, 5 one tapered end of said wedge adapted to coact with the tapered hole in said float and a weight having a tapered hole to coact with the other tapered end of said wedge whereby said float may be clamped to said cable.

10 2. In a salvaging apparatus, a cylindrical float adapted to float upon the surface of the water in a horizontal position, an intake check valve on the top of said float, a discharge check valve at the bottom of each end of said float, two vertical braces intermediate of the ends of said float and each having a vertical longitudinal tapered hole therethrough, a lifting cable for each of said tapered holes, 15 re-inforcing I beam braces in said float, a wedge having double tapered ends for each of said cables and a weight having a tapered hole for each of said wedges, whereby said float when submerged and filled with air may be locked to said cables to exert a lifting force 20 thereon.

25 3. In a salvaging apparatus, a buoyant submersible cylindrical float adapted to float in a horizontal position and having one top intake and two bottom discharge check ball valves to introduce and discharge air and water therefrom, two vertical braces in said float intermediate of its ends and each having a longitudinal hole therethrough with a 30 tapered portion from the top toward its approximate center of length, a lifting cable for each of said holes, a sectional tapered wedge to coact with each of said cables and its tapered hole to exert a gripping force on 35 each of said cables when said float is submerged, said discharge valves located one at either end of the bottom of said float, connecting hose means from said discharge valves to the water surface when said float is submerged, and valve means in said hose means 40 whereby all water may be discharged from said float if not perfectly horizontal and a desired air pressure maintained in said float.

45 4. In a salvaging apparatus for submarine boats, the combination of a boat having chambers located in the sides thereof, a door for each chamber conforming approximately to the hull of said boat and adapted to be swung open laterally at the top from bottom hinges, a threaded shaft acting in line with the lateral movement of said doors and having a 50 pin and slot connection for the opening thereof, valve means for flooding each chamber, a buoy in each chamber with signalling means attached thereto and to the interior of said boat, hawsers built-in to the hull of said boat for lifting same and each of which extend 55 from one of said chambers to its diametrically opposite chamber, a lifting cable in each of 60 said chambers attached to said built-in haw- 65

ser, a line connecting said cable and buoy to permit said buoy to rise to the surface of the water when the boat is submerged, floats with intake and discharge valve openings and connections thereto to the surface of the water when submerged and adapted to float in a horizontal position, said floats having two vertical braces intermediate of its ends and each brace with a longitudinal tapered hole therethrough and spaced the distance between the built-in hawsers of two adjacent chambers, and sectional double tapered wedges whereby said floats may be clamped to said lifting cables.

70 75 In testimony whereof, I affix my signature. 80
BENJAMIN FILBERT.
